METHOD OF RECOVERING EARTH COM-
PONENTS FROM WELLS

Meinhard H. Kotzebue, Tulsa, Okla.

Application December 6, 1935, Serial No. 53,141

11 Claims. (Cl. 166—21)

This invention relates to new and useful improvements in methods of recovering earth components from wells.

An object of the invention is to provide a method whereby recovery of hydrocarbons and other base earth components such as carbon dioxide and helium may be effected in a new and improved manner and specially substantially without waste and with a view of effecting conservation of the natural resources of the earth.

An important object of the invention is to carry out such method by means of a selective normally liquid absorption medium having affinity for the particular components which it is desired to recover.

Another object of the invention is to provide a method for recovering earth components from a well whereby the stream which is flowed from the well may be conducted through suitable apparatus for separating the absorption medium and taking off certain desirable components, and if desirable returning to the well with the absorption medium certain other components which are not to be retained at the surface.

The method involves certain other objects and advantages which will be hereinafter more particularly pointed out and for the purpose of illustrating the operation of the method and apparatus for carrying out the same, I have shown in the accompanying drawing a diagrammatical illustration of a well and apparatus located on the surface and connected with said well.

In the drawing, the numeral 10 designates the casing of a well, and 11 the usual casing head. As the invention has a wide use the well may be one producing gas, oil, or other fluids and/or liquids. The casing may be cemented as indicated in the drawing or it may merely be anchored in the well and the head provided with hold-down cables or rods 12 suitably fastened. In the producing sand or strata, it is customary to either perforate the casing or to provide a screen 13 which extends, as a rule, to the cap rock, or other overlying structure. The usual tubing 14 extends from the bottom of the well up through the head 11 and out through a stuffing box 15. The tubing may be connected to a T 16 from which a pipe 17 extends. A suitable valve 18 for controlling the flow may be connected in the pipe 17 near the T.

The pipe 17 is connected with the pipe 19 extending to the lower portion of an ordinary vertical absorber or separator. It is to be observed that no new equipment is employed in this method and any device or devices now in use or which may be put into use, and are suitable for the purpose, may be used. It is customary in the separation of hydrocarbons to provide a gas and liquid separator of any approved type 20 with staggering baffle plates 21. The fluid flow-

ing from the well and entering the lower portion of the absorber is under sufficient pressure to carry it upward therein. The heavier liquids or liquid hydrocarbons will be scrubbed out of the ascending fluid so as to collect in the bottom of the absorber. The gaseous fluids such as ethane and methane and others will ascend to the top of the absorber and pass out through a pipe 22 in the usual manner. These fluids may be conducted to a suitable device for further treatment or they may be otherwise conserved. Where such gases are of little value they may be disposed of in a suitable manner.

The liquid hydrocarbons are conducted from the bottom of the absorber 20, by way of a pipe 23, to a heat exchanger 24 and treated therein in the usual manner. The liquid hydrocarbons from the heat exchanger are then carried by way of a pipe 25 to a preheater 26 and thence by a pipe 27 to an evaporator 28. As is customary, the desired fractions are distilled from the absorption liquid in this evaporator. These desirable fractions or gaseous hydrocarbons or distillates are carried from the evaporator by a pipe 29, which may be connected with an ordinary gasoline plant or other treating apparatus which is not shown.

The absorption liquid or fluid being denuded or robbed of the desirable fractions or hydrocarbons collects in the bottom of the evaporator and is drawn therefrom by a pump 30 which is connected with the bottom of the evaporator by a pipe 31, the heat exchanger 24, a pipe 32, a cooling device 33 and a pipe 34. The absorption liquid passing through the heat exchanger 24 heats the liquid hydrocarbons which pass to and through the heat exchanger on their way to the evaporator, and the heating of the liquid hydrocarbon extracts heat from the separated absorption liquid, resulting in an initial cooling of the absorption liquid. The absorption liquid is further cooled in the cooler 33 to the desired temperature for return to the well. The heat exchanger 24 is not necessary to the successful operation of the present invention, but is desirable since it performs a heat exchange between the liquid hydrocarbons going to the evaporator and the denuded absorption liquid leaving the evaporator. This not only saves some of the heat in the denuded absorption material but reduces proportionately the amount of cooling necessary in the cooler 33. It is desirable to cool the liquid after it has passed through the heat exchanger.

The return absorption liquid discharged from the pump is delivered by a pipe 35 to pipes 36 and 37. The pipe 37 includes a valve 38 which is normally closed but which may be opened to permit a portion of the return liquid to enter the upper end of the absorber for the purpose of dampening or retarding the upward passage of the gaseous fluids and also for the purpose of re-

absorbing any desirable fractions. The main return line 36 extends to a chiller 39 which is connected with the casing head 11 by a pipe 40 including a control valve 41. The pipe 31, which 5 extends from the bottom of the evaporator, may have a valved outlet 42 so that any excess or surplus in the return fluid may be bypassed. This outlet 42 may be connected with a pipe 43 which is connected with a pump 44, which in turn is 10 connected by a pipe 45 with the return pipe 36 in advance of the chiller. Surplus products may be introduced into the system at this point or the circulating absorption liquid or fluid may be replenished by this connection or any other suitable manner, as by introduction into the evaporator.

Referring to the cycle of operation, it will be apparent that the absorption medium, which may be any one of the commercial absorption liquids 20 known in the art of refining petroleum oils such as gas oil, kerosene, or absorption oil having a boiling point between 400° and 600° Fahrenheit, or any one of the known absorption liquids having an absorbing attraction for carbon dioxide 25 or helium, depending on the nature of the material to be withdrawn from the well, may be pumped down the casing 10 and upon reaching the upper portion of the screen 13 or perforations in the casing just below the cap rock, will flow 30 outwardly into the sand or strata as indicated by the curved arrows. Among the known absorbents for helium are carbon disulfide, acetone, kerosene and gas oil; for hydrogen sulfur, dioxide and gelatin are good absorbents to eliminate 35 other gases; for carbon dioxide, triethylamine and monoethylamine are good absorbents for pressure absorption. In passing downwardly through the zone of the sand, the absorbing medium will become enriched with the hydrocarbons 40 or other components produced in such zone. Where the produced components are liquid they will admix with the absorption medium and where they are gaseous they will be carried out in solution. Owing to the flowing pressure this 45 absorption stream will pass upwardly through the tubing 14. At this point it might be well to state that the method could be reversed and the absorption stream conducted down the tubing and out into the sand, whereby the return stream 50 would pass up the casing; however, I prefer to use the method illustrated.

It will be seen that operating under usual conditions in a well producing no or very little liquid hydrocarbons, and a large amount of gaseous 55 hydrocarbons, it is almost impossible to recover heavy hydrocarbons without producing excessive amounts of the normal gaseous material. Where the bottom-hole pressure is particularly high, as per illustration, in excess of 2000 pounds, a 60 corresponding high pressure would be produced above the surface which is not only dangerous but interferes with a proper recovery. It is customary under such conditions to waste large volumes of valuable gases, either by discharging into the atmosphere or by burning as a torch. Such waste aside from the safety question is detrimental 65 to conservation of natural resources. Where an absorption liquid is pumped down into the well, it is possible to hold the pressure at the bottom of the well and to seal-off the gaseous hydrocarbons so that the stream which is delivered by the tubing will have a much lower pressure, as for instance, less than 1000 pounds and as such may be safely and economically handled. The fluid, that is, the absorption liquid and

such earth components as it has picked up from the well through the mutual action of the absorption liquid and the earth components, which is discharged from the tubing 14 is conducted by way of the pipes 17 and 19 to the absorber 20. 5 The lighter gases escape from the top of the absorber through the pipe 22 while the heavier hydrocarbons are carried out through the pipe 23 to the heat exchanger 24. The routine from the heat exchanger by way of the pipe 25, pre-heater 10 26 and pipe 27, to the evaporator 28 is in accordance with the common practice and it is not considered necessary to describe the same, except to say that the absorption medium is recovered in the bottom of the evaporator after the desirable 15 fractions have been removed. The recovered absorption medium becomes the return liquid and passes out through pipe 31, through the heat exchanger 24 and pipe 32 to the cooler 33. It is desirable to reduce the heat of the return fluid. 20 The circulation is maintained through the pump 30 which receives the absorption or return liquid from the cooler by way of pipe 34 and discharged it through pipe 35 into the return line 36 which is connected with the casing head 11 by the pipe 25 40. This liquid passes through the chiller 39 whereby its temperature is reduced to a degree which is desirable for recirculating in the well.

The natural laws of governing the absorption of various hydrocarbons, admixtures thereof and other materials existing in the ground such as helium, hydrogen, carbondioxide and the like are well known by those familiar with the art of extraction of such materials from the earth and their refining with which art the present invention is clearly allied, and for this reason the technicalities of absorption have not been entered into in this description, but it is obvious that the amount of material and the character of the material absorbed will depend to a large extent 40 upon the kind of absorption material, the pressures, temperatures, degree of contact, length of contact time and the proportionate amounts of absorbing material, which are used. Very successful results have been obtained by using a 45 heavy hydrocarbon liquid as the absorption medium for certain components, but various other media which are not hydrocarbons may be used. By passing the return liquid through the cooler 33 and the chiller 39 its temperature is 50 reduced so that its absorption efficiency is increased.

In some localities certain hydrocarbons or other components from the well may be picked up by the absorption liquid, and it being impractical to use the same, they may be returned to the well with the return stream. Following the laws of fractionation and absorption, the greater part of such returned products will remain in the producing zone; however those products which have a great affinity for the particular absorption medium used, will replace such returned products, or will permit further absorption of like material thereby preventing wastage. The cycle of operation may also be desirable as 65 an aid to counteract the heat of absorption, because heat is required to effect separation. It would be possible to introduce other gaseous or liquid material to replace the products taken from the subterranean basin in order to maintain pressure, regulate temperature or to disolve materials in the strata to more efficiently accomplish the purpose of this method.

It is to be understood that the invention is not to be limited to use in oil and gas wells as it may 75

be equally as well employed where a well is producing other earth components such as helium and carbon dioxide. Those skilled in the art as above referred to will be able to determine the particular character of the absorption medium necessary to recover the desired components. It would also be possible to select and recover certain earth components by employing an absorption medium for which such components had an affinity and which medium would not absorb the undesirable components. While the devices which have been illustrated are particularly adaptable to a gas and/or oil well, it is obvious that any devices suitable for the particular components being recovered may be used.

What I claim and desire to secure by Letters Patent, is:

1. In the art of wells, the method of recovering selected gaseous or liquid earth components which consists, in circulating a liquid absorption medium into the well and through the subterranean basin and out of said well, and removing from the subterranean basin by circulation and absorption the heavier normally liquid products having higher boiling points from normally gaseous mixtures and at the same time removing but a small proportion of components which are not condensable except under very high pressures and low temperatures.

2. In the art of producing gasoline from wells, the method of stripping the gasoline content from the natural gas by circulating a liquid absorbing medium having an affinity for the gasoline content through the well and its basin, removing a major portion of the gasoline content and a minimum proportion of natural gas, then separating the gasoline content from the saturated liquid absorbing medium, cooling the liquid absorbing medium, and re-circulating the liquid absorbing medium through the well and its basin.

3. In the art of wells, the method of recovering selected gaseous or liquid earth components which includes, circulating a selective liquid absorption medium into the well and through the producing strata, removing from the well selected components by said absorption medium, and then treating the stream flowing from the well to separate desirable components and then returning the liquid absorption medium to the well, whereby a cycle of operation is maintained.

4. In the art of wells, the method of recovering selected gaseous or liquid earth components from wells having an inherent gas pressure, which includes introducing a cooled liquid absorption medium into the top of the well and circulating it in and out of the well and through the producing strata surrounding the bottom of the well, and removing from the producing strata ascertained components having an affinity for the liquid absorption medium and leaving in the natural basin other components.

5. In the art of wells, the method of conservation of earth components which consists, in introducing a cooled selected liquid absorption medium into the well and circulating it therethrough also forcing said liquid absorption medium in sufficient quantity through the well for passing it through the producing strata, selecting from the producing strata by character of the absorption medium used portions of certain liquid and gaseous components and leaving in the strata usable portions of liquid and gaseous components, re-

turning the liquid absorption medium laden with the selected components to the surface, separating the usable components from the laden absorption medium, cooling the absorption medium, and returning the cooled liquid absorption medium to the well.

6. In the art of wells, the method of recovering selected gaseous or liquid earth components which includes circulating in and out of the well and through the producing strata a liquid absorption medium which has an affinity only for the selected components, and removing the selected components from the strata and leaving in the natural basin other components.

7. In the art of wells, the method of recovering selected gaseous or liquid components of the earth components found in petroleum bearing strata which includes, circulating in and out of the well an absorption liquid which has an affinity only for selected components of the petroleum removing only the absorbed selected components and the absorption liquid from the strata and leaving the other components in the natural basin.

8. In the art of wells, the method of conservation of earth components which includes, circulating a liquid absorption medium in and out of the well and through the producing strata surrounding the well, which liquid absorption medium has an affinity for the gasoline content and certain gaseous contents of the strata, and removing from the strata and well a fluid consisting of a major portion of gasoline and the selected gas, separating the gasoline and gas from the liquid absorption medium, and re-circulating the liquid absorption medium through the well.

9. In the art of wells, the method of conservation of earth components which includes, circulating a liquid absorption medium in and out of the well and through the producing strata, which liquid absorption medium has an affinity for the gasoline content, and removing from the strata a fluid consisting of a major portion of gasoline, separating the gasoline from the liquid absorption medium, and re-circulating the liquid absorption medium through the well.

10. In the art of wells, the method of conservation of earth components which includes, circulating a liquid absorption medium in and out of the well and through the producing strata, which liquid absorption medium has an affinity for the gasoline content, and removing from the strata a fluid consisting of a major portion of gasoline, separating the gasoline from the liquid absorption medium, cooling the liquid absorption medium, and re-circulating the cooled liquid absorption medium through the well.

11. In the art of wells, a method of recovering selected gases or liquid earth components which includes, forcing a liquid absorption medium having an affinity for the components to be recovered, downwardly through the well and out into the producing area in a quantity sufficient to fill the producing area adjacent to the well and block off the direct passage of gases to the well, withdrawing the liquid absorption medium and absorbed earth components from the producing strata through the well, separating the liquid absorption medium and the absorbed components, and returning the liquid absorption medium through the well and producing strata.

MEINHARD H. KOTZEBUE.
